COMBINED WRIST MOUNTED PENCIL AND SHEATH THEREFOR

Kenneth E. Malberg, 1415 W. North St., Apt. 514,
Anaheim, Calif. 92801

Filed Dec. 6, 1973, Ser. No. 422,589

Term of patent 3½ years

Int. Cl. D19—06

U.S. Cl. D19—35

FIG. 1

FIG. 2

FIG. 1 is a perspective view of a combined wrist mounted pencil and sheath therefor showing my new design, wherein the pencil is withdrawn from the sheath; and

FIG. 2 is a rear perspective view showing the pencil inserted in the sheath.

I claim:

The ornamental design for a combined wrist mounted pencil and sheath therefor, substantially as shown and described.
